UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-OVEN DOOR AND OPERATING MEANS THEREFOR.

Application filed October 16, 1919. Serial No. 330,989.

To all whom it may concern:

Be it known that I, JOSEPH BECKER, a citizen of the United States, residing in Pittsburgh, in the county of Allegheny and 5 State of Pennsylvania, have invented a new and useful Improvement in Coke-Oven Doors and Operating Means Therefor, of which the following is a specification.

This invention relates to coke ovens and 10 has for its essential object the provision of a vertically-slidable hinged oven door for opening and closing the mouth of a coking chamber of said oven, and a removable manually-operable door-lifting and operating 15 means that may be moved into operative relation with any of the oven doors of a coke oven battery and then operated to open the door. The manually-operable door-lifting and operating means of the present invention 20 is exceedingly simple and economical in construction and is adapted to replace expensive, heavy and complicated door operating machinery now in use. The invention is of particular utility in coke oven plants 25 or batteries of relatively restricted size and capacity, although it may obviously be employed in coke oven units of whatever magnitude with satisfactory results.

The invention also includes among its objects an increasing of the efficiency of operation of an apparatus of the character set forth combined with great simplicity in design and construction and such other results or advantages in construction and operation 35 as are found to obtain in the structures hereinafter described or claimed.

In the accompanying drawings, forming a part of this specification, and showing, for purposes of exemplification, a preferred 40 form and manner in which the invention may be embodied and practiced, but without limiting the claimed invention specifically to said illustrative instance or instances;

Figure 1 is a fragmentary side elevation 45 of a coke oven battery equipped with an oven door and a door operating means constructed in accordance with the invention;

Fig. 2 is a vertical sectional elevation taken in a plane indicated by the line 2-2 50 of Fig. 1;

Fig. 3 is a vertical sectional elevation taken in a plane indicated by the line 3-3 of Fig. 4;

Fig. 4 is an enlarged front elevation of the lower portion of an oven door and showing

the operating means in position for operating the door;

Fig. 5 is a horizontal section taken in a plane indicated by the line 5-5 of Fig. 1;

Fig. 6 is a horizontal section taken in a 60 plane indicated by the line 6-6 of Fig. 4; and

Fig. 7 is a perspective of a coke oven door.

The same characters of reference indicate 65 the same parts throughout the several views.

In its present embodiment, the invention is employed in connection with a coke oven battery of the by-product type, which battery embodies in its construction a plurality 70 of elongated coking chambers 21 arranged side by side with crosswise extending heating walls 22, the latter being equipped with the usual flame flues for generating the heat to coke the charges of coal in the coking 75 chambers 21. The ends of the heating walls 22 are formed with vertically extending recesses 23 having shoulders 24 to constitute jambs respectively positioned on the opposite sides of and at the end of a coking chamber 21. The top of the coking chamber 21 is recessed as shown at 25, said recess extending inwardly from the outer face of the side of the battery and including a shoulder 26 disposed approximately in the same plane 80 as the shoulders 24 of the jambs and connecting them together. The end faces of the heating walls are each braced by a pair of vertical parallel buck stays 27 which extend from the top of the battery downwardly beyond the bottoms 28 of the several coking chambers and brace the battery structure therebeneath, as shown in Figs. 1 and 2.

Extending lengthwise along the side of the battery in a plane beneath the operated 95 door is a horizontal platform 29, the outer edge of which is supported by a series of vertical uprights 30. This platform supports a pair of rails 31 constituting a track on which run the usual coke handling devices.

The mouth of each coking chamber is closed by a coke oven door 32 consisting essentially of a metallic outer shell 33 and the usual internal refractory lining 34 supported 105 by said outer shell. As shown in Figs. 5 and 6 the outer shell 33 is formed with opposite vertically extending shoulders 35 adapted to rest against the shoulders 24 of the jambs 23 at the opposite sides of the 110

mouth of a coking chamber. That portion of the door which projects within the coking chamber beyond the shoulders 24 and 26 is made lower than the outside part of the door and the height of the coking chamber, so that a horizontal shoulder 36 is formed at the upper edge of the door which is adapted to engage the horizontal shoulder 26, as shown in Fig. 2: this construction permits the door 32 to be slid vertically, when in position at the mouth of a coking chamber, a sufficient distance to loosen the door from the luting that is applied to fill up the cracks between the door and the mouth of the coking chamber.

The front face of the metallic shell 33 of each door is provided with an upper outwardly projecting bracket 37 and a lower similarly projecting bracket 38, connected together, if desired, by a vertical bracing web 39. Bored clear through the upper bracket 37 is a vertically extending hole 40, and in alignment with said hole 40 is a socket 41 bored in the lower bracket 38 and terminating above the bottom of said bracket, as shown in Figs. 2 and 3. Mounted at its upper end in the hole 40 and at its lower end in the socket 41 is a vertical rod 42 on which is pivotally supported a hinge 43 embodying a vertical member 44 having upper and lower arms 45 and 46 which embrace the vertical rod 42 of the coke oven door and also having upper and lower arms 47 and 48 extending sidewise of the door, as shown in Figs. 1, 4 and 5. The arms 47, 48 extend to and encircle a vertical rod 49 slidably supported in bearings 50, 51 located respectively below the arms 47 and 48. With this construction, the coke oven door may swing about the vertical axis of the rod 49 to open and close the mouth of the coking chamber 21 and the door may further swing when opened about the axis of the vertical rod 42; in addition to its swinging movement the coke oven door may slide vertically with respect to the jambs at the mouth of the coking chamber permitting the door to be loosened from the luting that fills the cracks between the door and the mouth of the coking chamber.

In order to effect a vertical sliding movement of the door to loosen it from its luting and then to swing the door into open position on its hinge, the invention provides a removable, manually-operable door-lifting and swinging means. In its preferred embodiment, this means consists of a roller carriage 52 structurally independent of the door and adapted to be moved into position for lifting and swinging the door. Said roller carriage embodies in its construction a truck mounted on a small roller 53 and provided with a projecting horizontal abutment 54 that is adapted to enter the space between the upper and lower hori-

zontal flanges 55, 56 projecting outwardly from the bottom of the coke oven door. As shown in Fig. 3 said flanges 55, 56 are provided with holes 57, 58 and the abutment 54 is provided with a hole 59 that registers with the holes 57, 58 when the carriage is in operative position with respect to the coke oven door. A pin or any suitable removable coupling device may be inserted between the aligned holes 57, 59, 58 for the purpose of retaining the roller carriage in its operative position.

Mounted on the roller carriage 52 is a jack 60 of any preferred construction provided with the usual lifting rack bar 61 and the usual operating handle 62. When the carriage is in its operated position with respect to the coke oven door, the head 63 of the vertical rack bar of the jack is adapted to enter a socket 64 formed in the bottom face of the lower bracket 38. The head 63 of the lifting bar 61 is guided into the socket 64 by means of a vertical flange 65 depending from the bracket 38 at the rear of the socket 64. With the roller carriage 52 moved into the operative position shown, the jack 60 may be operated in the usual way to raise the lifting bar 61 into the socket 64 and lift the door to loosen it from its luting. As soon as this has been accomplished, the jack is locked in position and the door may be swung open supported on the roller 53 of the carriage, while the hinge members act substantially to guide the door in its swinging movement. In closing the door it is swung to closed position supported by the carriage 52 and when the door is in proper position for closing the mouth of the coking chamber the lifting bar 61 of the jack is lowered, whereupon the roller carriage 52 may be moved into position for operating another door of the coke oven battery.

Secured to the web 39 on the front face of the door is a spring wedge 66 having an inclined portion 67 that is adapted to engage a horizontal wedge bar 68 removably supported between the buck stays on the opposite sides of the door. The lowering movement of the door at the termination of the closing operation effects a wedging engagement of the inclined portion 67 of the spring wedge 66 with the wedge bar 68 to firmly lock the door in closed position. In opening the door the lifting movement moves the inclined portion 67 out of wedging engagement with the bar 68, so that the bar 68 may be removed and the door opened in the manner herein before described.

The invention as hereinabove set forth is embodied in a particular form of construction but may be variously embodied within the scope of the claims hereinafter made.

I claim:

1. The combination of a chamber oven, a

door fitted to the end of the oven to close the same and vertically movable to be disengaged from its seat, hinging means for the door permitting the latter to be raised 5 and to be swung outwardly, and elevating means for sliding the door vertically upward from its closed position to release it from its seat, said elevating means comprising means for attachment to the door and 10 a roller turning in vertical planes and serving as a support for the weight of the door first during its vertical movement and afterwards throughout the entire period while the door is out of closed position, said roller 15 being adapted while supporting the weight of the door to then travel horizontally in an arc concentric to the hinging means of the door, substantially as specified.

2. The combination with a chamber oven, 20 of a door hingedly mounted for vertical sliding and swinging movements from its closed position at the mouth of said chamber oven, elevating means applied directly to the door for causing said vertical sliding movement, and a roller carriage attached to said door and supporting said elevating means and said door first during the sliding movement and afterwards throughout the entire period while the door is out of closed position, substantially as specified.

3. The combination with a chamber oven, 25 of a door hingedly mounted for vertical sliding movement and swinging movement from its seat at the opening of the oven, and elevating means applied directly to the door and supported independently of the hinge structure for first causing said vertical sliding movement and afterwards constituting a support for the door throughout the entire 40 period while the door is out of closed position, substantially as specified.

4. The combination with a chamber oven, 45 of a door hingedly mounted for vertical sliding movement and swinging movement from its seat at the opening of the oven, elevating means applied directly to the door for first causing said vertical sliding movement, and a rolling carriage supporting said elevating means during its vertical movement and afterwards throughout the entire 50 period while the door is out of closed position, substantially as specified.

5. The combination with a chamber oven, 55 of a door at the opening thereof, a vertical support carried by said door, another vertical support mounted on the side wall of the oven structure, and a hinge connection between said supports, said hinge connection having both rotary and sliding connections 60 with both of said supports.

6. The combination with a chamber oven, 65 of a door at the opening thereof, a vertical support carried by said door, another vertical support mounted on the side wall of the oven structure, and a hinge connection be-

tween said supports, said hinge connection having both a rotary and sliding connection with the support on the door.

7. The combination with a series of chamber ovens of hinged closures for said ovens, a carriage provided with means for attachment and detachment to any closure and with means to move the closure to which it is attached in the plane of the latter to break its seal prior to the swinging of the closure on its hinges to its open position, said carriage being adapted to support the closure to which it is attached during the breaking of the seal and throughout the entire period while the closure is out of closed position, substantially as specified.

8. The combination with a chamber oven, 80 of a door hingedly mounted in the opening of said chamber oven, a roller carriage for supporting the door while swinging on its hinge, said carriage having a projecting lug for making a connection with a portion of the oven door, and a jack mechanism supported by said carriage for lifting the door to loosen it from the oven preliminarily to swinging it on its hinge, said carriage supporting the door during the lifting operation and afterwards throughout the entire period while the door is out of closed position.

9. The combination with a chamber oven of a hinged closure for said oven, a carriage provided with means for attachment to the closure and with means to move the closure in the plane of the latter to break its seal prior to the opening of the closure, said carriage supporting the closure during the entire period while the closure is out of closed position.

10. An operating attachment for a door 105 mounted to swing pivotally and to slide vertically on its hinges and designed to be sealed in its closed position and having a downwardly disposed engaging member and an attaching lug, which attachment comprises a roller carriage provided with an elevating means adapted to engage the downwardly disposed engaging member to lift the door and with a lug for pivotal connection to the attaching lug, substantially as 110 specified.

11. An operating attachment for a door 115 mounted to swing pivotally and to slide vertically on hinges and designed to be sealed in its closed position and having an engaging part and an attaching member, which attachment comprises a carriage provided with an elevating means adapted to engage the engaging part on the door and with means for connection to the attaching member on said door, substantially as specified.

12. An operating attachment for a door 120 mounted to swing pivotally and to slide vertically on hinges and designed to be sealed in its closed position and having an engag-

ing part and an attaching member, which attachment comprises a carriage provided with an elevating means adapted to engage the engaging part on the door and with means for connection to the attaching member on the said door, and a handle for operating the elevating means and for swinging the carriage and door about the hinge of the latter as a center, substantially as described.

13. The method of operating a coke oven

door mounted on hinges at one side for vertical and horizontal movement and adapted to be sealed in position which consists in first applying a force in the plane of the door and independently of the hinge structure to break its seal and thereafter supporting and swinging the door by the force applying means, substantially as described.

In testimony whereof I have hereunto set my hand this 6th day of October, 1919.

JOSEPH BECKER.
